UNITED STATES PATENT OFFICE.

ALONZO W. CRAM, OF LITCHFIELD, ILLINOIS.

IMPROVEMENT IN ELEVATORS.

Specification forming part of Letters Patent No. 140,017, dated June 17, 1873; application filed May 8, 1873.

To all whom it may concern:

Be it known that I, ALONZO W. CRAM, of Litchfield, in the county of Montgomery and State of Illinois, have invented an Improved Elevator, of which the following is a full, clear, and exact description, reference being had to the accompanying drawing and the letters of reference marked thereon making part of this specification, in which—

Figure 1 is a vertical sectional view. Fig. 2 is a top-plan view on the line x x , Fig. 1. Fig. 3 is a top-plan view of the mouth-piece.

The object of my invention is to provide an apparatus for raising and elevating grain, coal, sand, dirt, &c., by injecting jets of steam into a chamber or cylinder, and which connects an inlet or suction tube with a discharge or delivery tube. The nature of my invention consists in inviting the inlet and discharge tubes of the elevator, by means of an annular steam-chamber having a series of jets or cone-shaped nozzles. Within this steam-chamber is a central opening, which, in connection with the inlet and discharge tubes, forms a continuous straight passage for the material to travel through, without angles or curves, and of a uniform, or nearly so, diameter throughout. The cone-shaped nozzles are so arranged that their jets of steam are discharged directly through the delivery-tube, and, from their arrangement, form, as it were, an annular jet, the steam from which impinges against the wall of the tube in such manner as to leave, directly through its center, and on a direct line with the inlet and discharge orifices of the tubes, a hollow cone-shaped vacuum-passage. The great advantage of this arrangement of jets over a jet that discharges through the center of the delivery-tube is found in the fact that, while with the latter, should a stone or other hard substance, of such dimensions as to nearly fill its diameter, enter the tube, it would almost inevitably clog the passage so soon as it passes the steam-jets, and which would render the device inoperative, with my arrangement of nozzles, and which form an annular jet round the wall of the tube, leaving an unobstructed elevating and discharge vacuum-passage directly through the tube, all danger of the tubes clogging is securely guarded against.

The construction and operation of my inven-

tion are as follows: A is the inlet or suction tube, which is constructed of any suitable material, and is of any desired dimensions. To the lower section of this tube is secured the receiving end section or tube B, and which is of a hollow cone or funnel shaped form, the enlarged mouth of which facilitates the entrance of the material to be elevated, while the strainer cross-bars b prevent the entrance of any hard substance sufficiently large to endanger the clogging of the tube. At the opposite or upper section of this tube A is the steam-chamber, which consists of a tube, C, outer casing or jacket C', and which is so arranged, in connection with the tube C, as to leave a cone-shaped steam passage or chamber, c, into which leads a circular series of jets, a a. This chamber is formed of any suitable material, and connected to the tube A by any convenient means. To this chamber or passage c, by means of an opening, d, is connected a steam-supply pipe, D, which is fed from a boiler or any other suitable steam-vessel. E is the discharge or distributing tube, and is constructed of any suitable material. At its lower section is secured a hollow cap or cone-shaped cylinder or neck, E', and which fits over the outer casing C' of the steam-chamber, as clearly shown in Fig. 1. At the upper section of this tube E is secured a short tube or section, F, around the forward section of which is secured, by means of shoulders or bearings f f', a hollow cone-shaped tube or hood, F'. This projects beyond and around the outer opening of the tube F, and is so arranged, in connection with the tube, as to provide a passage, f', and which tends greatly to break the force of the discharge, and to reduce the bulk of the material by providing, as it does, a vent for the steam.

Instead of steam being used, compressed air or other aeriform fluid may be substituted, and which will accomplish, in an equally effective manner, the same advantageous results.

From the foregoing description the operation of my improved elevating apparatus will readily be understood. Its several features are constructed and connected as described; and the discharge-tube A is lowered into the hold of the vessel or other receptacle containing coal or grain, or in contact with the sand or other

material which it is desired to elevate, and there held or secured in such manner as to allow of the free passage of the material into the tube A, the funnel-mouth end piece B facilitating the operation, while the strainer-bars b b prevent the entrance of any lumps or stones which are sufficiently large to endanger the choking or clogging of the tubes. Steam, compressed air, or other like motor is now supplied through the pipe D, and soon fills the passage c of the steam-chamber, and, escaping through the nozzles a a, it is discharged directly into the delivery-tube E, as indicated by arrows in Fig. 1; and, being thrown and impinging directly against the inner wall of the tube, forms, as it were, an annular jet, and which hollow cone or circle of steam produces a vacuum, which, being directly on a line with the center of the entrance and discharge tubes, elevates the material in the most rapid manner by the immense force of the atmospheric pressure thus produced. And it is then driven through the discharge-tube by the jets of steam until it reaches the end of the neck F, when the force of the pressure is lessened by the steam or other aeriform liquid escaping through the vent-passage f', and which reduces its bulk and permits of the material being delivered in a more compact manner.

Besides the uses of an ordinary elevator, as

hereinbefore described, the device is admirably adapted for leveling roads and other engineering purposes.

What I claim as new, and desire to secure by Letters Patent of the United States, is—

1. The inlet or suction tube A, the discharge-tube E, steam-chamber c, formed as shown, and having a series of annular jets a a, and an opening, d, for the supply of steam, the whole being constructed, combined, and arranged to operate substantially as described.

2. In combination with the inlet-tube A, steam-chamber having a series of jets, a a, arranged as shown, the discharge-tube E end-tube F and hood F', and vent-passage f', the whole being constructed and connected so as to operate substantially as described.

3. The chamber c and jets a a, the tube A, having a funnel-shaped mouth, B, with strainer-bars b b, tube E, having end tube F, provided with a hood, F', so secured as to leave a vent-passage, f', the whole being combined and arranged to operate substantially as described.

In testimony whereof I have signed my name to this specification in the presence of two subscribing witnesses.

ALONZO W. CRAM.
